RAZOR BLADE SHARPENING DEVICE

Albert Ruckgaber, Stapleton, N. Y.

Application January 22, 1929, Serial No. 334,172

27 Claims. (Cl. 51—84)

This invention relates to razor blade sharpening devices, and has for its primary object and purpose to provide a simply constructed and efficiently operating device whereby razor blades 5 may be quickly honed and stropped to provide the same with a keen cutting edge.

Generically considered, the present invention comprehends a device of this kind embodying means whereby the edge of the razor blade may 10 be first honed and then stropped, or on the other hand, the honing and stropping operations may take place concurrently with a simultaneous relative movement of the blade with relation to the honing and stropping means, at the election of 15 the user.

In the attainment of the above purpose, in one practical embodiment of the invention, I provide 20 annular honing and stropping members alternately arranged in juxtaposed relation and respectively carried by separate supporting axes, together with means for relatively shifting said supporting axes to thereby position the centers of rotation of the honing and stropping members so that the two sets of members will be 25 eccentrically related to each other and only one set of said members positioned for engagement with the edge of the razor blade, or the axial centers of said two sets of members may be disposed in coinciding relation so that the peripheral 30 surfaces of said members are all concentric to a common center and disposed in the same plane for simultaneous engagement with the edge of the blade.

It is another important object of my invention 35 to provide an improved means for mounting and supporting a razor blade in operative relation to the honing and stropping members and means for moving said blade holder together with the blade secured therein axially of the rotatable 40 honing and stropping members so that all portions of the blade edge will be equally acted upon by said honing and stropping members.

It is another important object of my invention 45 to provide a device of the above character particularly designed for the purpose of sharpening double edge blades such as are used with so-called safety razors, and to provide two sets of the honing and stropping members above referred to and means operating automatically in the rotation 50 of said members to manipulate the blade holder and alternately position the opposite sides of the edges of the blade in engagement with the respective sets of honing and stropping members.

It is a further general object of my invention 55 to provide a razor blade sharpening device hav-

ing the above referred to advantageous features and in which the several parts thereof, together with the operating means for the honing and stropping members, is very compactly arranged, so that the device as a whole is of relatively small bulk, and the several cooperating parts thereof operating in a positive and reliable manner, and not liable to be relatively displaced or get out of order when the device is subjected to shocks or jars incident to abusive handling.

With the above and other objects in view, the invention consists in the improved razor blade sharpening device and in the form, construction and relative arrangement of the several parts thereof as will be hereinafter more fully described, illustrated in the accompanying drawings, and subsequently incorporated in the subjoined claims.

In the accompanying drawings, in which I have shown one simple and practical embodiment of 20 my present improvements, and in which similar reference characters designate corresponding parts throughout the several views,—

Figure 1 is a top plan view of a razor blade sharpening device constructed in accordance 25 with one form of the invention;

Fig. 2 is a side elevation thereof;

Fig. 3 is an end elevation;

Fig. 4 is a horizontal sectional view taken substantially on the line 4—4 of Fig. 2;

Fig. 5 is an enlarged detail section taken on the line 5—5 of Fig. 1, showing the honing members disposed in operative position for engagement with the razor blade;

Fig. 6 is an enlarged sectional view taken substantially on the line 6—6 of Fig. 1;

Fig. 7 is a similar sectional view taken on the line 7—7 of Fig. 4;

Fig. 8 is a view similar to Fig. 6 on a reduced scale illustrating the means for automatically 40 manipulating and positioning the razor blade;

Fig. 9 is an enlarged detail section showing the honing members disposed in an inoperative position and the stropping members engaged with the edges of the razor blade, and

Fig. 10 is a sectional view similar to Fig. 5 taken on the line 10—10 of Fig. 9.

The essential feature of the present application, resides in the mounting and arrangement of the two sets of rotatable honing and stropping members and the means for relatively shifting the centers of rotation of the honing and stropping members in each set whereby the opposite edges of a razor blade may be simultaneously engaged by the honing and stropping members in each 55

set, or the blade edge may be engaged by only the honing members or the stropping members at the will of the user; and secondly, in the means for manipulating and positioning the edges of the razor blade with respect to the honing and stropping members. For the purpose of illustrating these novel features of the invention, I have shown one mounting and arrangement of the several parts in the accompanying drawings which however, is largely suggestive, as the essentials of the invention might also be otherwise embodied in an operative device for practical operation by other means than the manually actuated instrumentalities illustrated in the drawings.

Referring now to the drawings, I have shown the parts of the device operatively mounted and supported between the vertically disposed end plates 5 and 6 respectively which are rigidly fixed at their lower ends upon a suitable base 7. A third vertically disposed plate 8 also fixed at its lower end to the base 7 is spaced inwardly from the plate 5. The plates 6 and 8 are provided at corresponding points with vertically extending slots 9 opening upon the upper edges of said plates, the purpose of which will presently become apparent.

The two sets of honing and stropping members are arranged in closely adjacent relation to each other between the spaced plates 6 and 8, and since they are of identical construction, the specific description of one set will suffice for both. Various arrangements might be devised whereby the alternately arranged honing and stropping members may be eccentrically shifted relative to each other so that either the honing or the stropping members may exclusively contact with the edge of the razor blade to be sharpened. In one simple and practical construction, I provide a hollow or tubular shaft 10 which is formed in spaced relation to each of its ends and on the outer side thereof with longitudinally spaced circumferential ribs or flanges 11. These flanges are of sector shape form and extend through an arc of somewhat less than 180°, and thus providing between the adjacent flanges, grooves or spaces 12 of similar form.

The end faces 13 of the ribs 11 extend from the bore of the shaft 10 in parallel relation to a diametric plane intersecting the shaft axis. The wall of the hollow or tubular shaft 10 from these end faces 13 of the ribs or flanges and the ends of the grooves 12 is cut away or removed as indicated at 14 to accommodate the elongated metal block 15. This block in cross section, is a counter-part of the section of the shaft 10 which is provided with the ribs 11, except that the spaced sector shaped ribs or flanges 16 of said block are positioned relative to the opposite ends of the block so that when the block is fitted into the opening 14, the ribs or flanges 16 thereof will be intermediate of the planes of the ribs or flanges 11 carried by the hollow shaft 10, and in line with the spaces or grooves 12 between the flanges 11.

In assembling these parts, a shaft 17 is first inserted through the hollow shaft 10, said shaft 17 being of appreciably less diameter than the internal diameter of the shaft 10. The block 15 is then inserted through the open side 14 of the shaft 10, said block being provided in its inner face centrally thereof with the groove 18 of the same radius as the shaft 17 to closely fit against one side of said shaft. The end faces 19 of the ribs or flanges 16 on the block 15 are disposed in parallel relation to the end faces 13 of the ribs or

flanges 11 and the block 10 is then rigidly secured at its opposite ends to the shaft 17 by means of the screws indicated at 20.

The hollow shaft 10 and the shaft 17 are now suitably held with their axial centers coinciding with each other, and therefore, with the outer peripheral surfaces of the flanges or ribs 11 and 16 concentrically disposed with respect to said coinciding centers on the same radius. There is now passed over the assembled parts a ring or annulus 21 of hard rubber or other suitable material, the internal diameter of which is such that it may be closely seated upon one of the end ribs or flanges 11 of the shaft 10 and fixedly secured thereto by the screws indicated at 22 which are countersunk in the outer face of said annulus. A relatively thin ring or layer 23 of leather is tightly engaged upon the outer face of the annulus 21 and has internal projections 24 extending into the countersinks formed by the heads of the screws 22 to prevent circumferential shifting movement of the leather ring. However, any other desired means may be provided for this purpose. This leather ring 23 constitutes one of the series of stropping members, and it will be understood that said ring and the annulus 21 are fixed only to the rib or flange 11 of the shaft 10, said ring and annulus at the opposite side of the shaft being out of line with the ribs or flanges 16 of the block 15 and in register with one of the annular grooves or spaces 25 which are formed by the latter ribs. When the stropping ring 23 revolves around its axis, and honing ring 26 revolves around its axis, the outer surface of revolution is cylindrical.

An annular honing member 26 is next assembled and is moved to position upon the outer circumferential face of the end rib or flange 16 of the member 15 to which it is secured by screws 27. The thickness of this ring is equal to the combined thickness of the annulus 21 and the leather stropping ring 23 secured to the rib 11 of the shaft 10, and is opposed to one of the grooves or spaces 12 between adjacent flanges or ribs 11.

There is sufficient clearance between the opposed side faces of the honing member or ring 26 and the annulus 21 and stropping ring 23 to permit of their free relative shifting movement. Additional stropping members and honing members are thus alternately assembled upon the ribs or flanges 11 and 16 of the parts 10 and 15, and it will be apparent that in any displacement of the shaft 17 radially of its axis relative to the shaft 10 or vice versa, the honing members and the stropping members will partake of such movement, and the outer peripheral surfaces thereof will assume an eccentric relation to each other to a degree corresponding to the extent to which the axial centers of the two shafts may be moved out of coinciding relation.

After the two sets of honing and stropping members have been assembled as above described, they are mounted in the supporting plates 5, 6 and 8. The plate 5 is provided with short vertical slots which receive one end of the shafts 17, the other ends of said shafts being movable in similar slots 29 provided in bracket plates 28 which are spaced from the outer face of the plate 6 in opposed relation to the slots 9 therein and are rigidly fixed at their lower ends to said plate. Between these brackets and the plate 6 a horizontally slideable bar 30 is disposed and a similar bar 31 is also positioned between the plates 5 and 8, said latter bar having one of its ends disposed through a suitable guide opening formed

in an inturned flange 32 on the plate 5 and adjacent its other end being slotted as at 33 to receive a guide pin or screw 34 fixed in the plate 8. The slide bar 30 is provided adjacent its opposite ends with similar slots 35 to receive the guide screws 36 fixed in the plate 6.

Each of the slide bars 30 and 31 is provided in its inner face and opposed to the vertically extending slots 9 in the plates 6 and 8 with the 10 obliquely inclined recesses or channels 37 which are adapted to receive the reduced ends 38 of the hollow shafts 10 which project laterally beyond the plates 6 and 8 respectively. Each of these grooved or channelled areas 37 of each slide 15 bar is further provided with a slot 39 extending through the bar and obliquely inclined in an opposite direction with relation to the recess or channel 37. Through these slots 39, the ends of the shaft 17 extend. It will be understood 20 that the width of the channel or recess 37 and the width of the slot 39 is such as to closely receive the ends of the shafts 10 and 17 respectively, so that the edges of said channels and slots form bearings for the shaft ends.

25 Any preferred means may be provided for shifting the bars 30 and 31. However, for this purpose, I have shown link members 40 pivoted at one of their ends as at 41 upon the plates 6 and 8 respectively, and connected at their other ends by a cross rod 42 carrying a suitable handle member 43. The links 40 have loose pivotal connection intermediate of their ends with the corresponding ends of the bars 30 and 31 as indicated at 44. For the purpose of yieldingly holding the 30 bars 30 and 31 in their adjusted positions, the upper edge of the bar 30 is provided with spaced notches 45 to receive the free end of a leaf spring indicated at 46 which is suitably secured at its other end to the plate 6.

40 Also various arrangements of gearing might be provided for the purpose of relatively rotating the two sets of honing and stropping members while permitting of the relative axial displacement of the members in each set as above referred to. As herein shown, this operating means may consist of a relatively wide gear 47 fixed upon a shaft 48 journalled at its ends in the plates 5 and 8 and actuated by a suitable operating handle 49 releasably connected with said shaft by the clutch 50.

To the inner end of said shaft a pinion 51 is secured and meshes with a gear 52 on a shaft 53 journalled at its ends in the plates 6 and 8 and centrally located below the honing and stropping members. Between the slide bar 31 and the 55 plate 8 a relatively narrow gear 54 is suitably fixed to the reduced end 38 of each of the shafts 10 and a similar gear 55 is also secured upon the corresponding end of each shaft 17 between the slide bar 31 and the plate 5. These gears have constant meshing engagement with the teeth of the wide gear 47 as shown in Fig. 7 of the drawings. The gear teeth are of sufficient length and so formed as to permit of the relative planetary shifting movement of the gears 54 and 55 while 60 maintaining the meshed engagement of said gears with the gear 47.

I have also devised a novel mounting for the razor blade holder and means for turning or manipulating said blade holder automatically so as to present the opposite sides of the blade edges in contacting engagement with the honing and stropping members.

As shown, parallel guide rods 56 are fixed at their ends in the plates 5 and 8 and parallel U-shaped metal straps 57 extending under the two

sets of honing and stropping members and at right angles to the axes thereof. These metal straps 57 carry suitable bearings indicated at 58 which are slidably engaged upon the guide rods 56. The upper ends of these straps 57 are respectively connected with each other by the metal plates or bars 59 which project above the straps 57 and are connected adjacent their opposite ends by the cross rod 60. To opposite ends of these rods links 61 are pivotally connected at one of their ends and have their other ends pivotally attached in spaced relation to each other as shown at 62 to opposite ends of a razor blade clamping device indicated at 63. The specific construction of this blade holder or clamping device constitutes no essential feature of the present invention, and it will suffice to state that it consists generally of two narrow metal clamping plates between which the central portion of the blade is detachably secured and clamped by 10 means of a clamping screw connecting the two plates which passes through an opening in the blade. One end of each of the parts of the clamping device is provided with angular wings or flanges extending in opposite directions to 15 which the ends of the respective pairs of links are pivotally connected as shown in Fig. 6 of the drawings. The two sets of honing and stropping members are disposed in closely adjacent relation so that the razor blade mounted in the holder 20 will bridge the space therebetween and rest at its opposite edges upon the respective sets of the honing and stropping members.

The blade and its holder, together with the links 61 are yieldingly held in this position and the 25 blade edges pressed closely upon the peripheral surfaces of the honing or stropping members by means of suitable coiled springs 64 which surround the opposite ends of the rods 60 and have one of their ends fixedly secured to the bars 59 30 while their other ends are suitably attached to the respective link members.

Upon the shaft 53 spaced members 65 forming a cam track 66 are fixed. The slide bearing 58 carries a roller 67 engaged in the cam track 66. 45 Thus, it will be understood that when rotation is transmitted to the shaft 53 through the gearing 51 and 52, the frame carrying the blade holder will be reciprocated axially of the two sets of honing and stropping members, and the edges of 50 the blade will therefore, be moved longitudinally over the surfaces of the rotating members with which they may be engaged.

At the end of the reciprocating movement of the blade holder in one direction, the holder and 55 the blade are turned or rotated through an arc of 180° so as to present the opposite beveled sides of the cutting edges of the blade to the honing and stropping members. For this purpose, there is suitably secured to each of the hollow shafts 10 60 at relatively opposite ends of the ribbed or flanged sections of said shafts, the cam members 68. These members are adapted to respectively engage obliquely inclined flanges 70 of the lugs 69 on one of the links 61 in each pair extending in relatively opposite directions from the blade holder 63.

Having now described the several parts of the device, its operation will be understood as follows: Assuming that the slide bars 30 and 31 are in the positions indicated in Figs. 3, 4 and 7 of the drawings, it will be seen that the ends of the shafts 10 and 17 have a bearing support in the corresponding ends of the channels 37 and slots 39 respectively, in the slide bars and in view of the eccentric relation of said end portions of 75

the channels and slots, it will be seen that the shafts 10 are depressed while the shafts 17 are raised or supported at a higher elevation so that said shafts rotate about separate centers in vertically spaced relation to each other. Therefore, upon reference to Figs. 5 and 6 of the drawings, it will be seen that the honing members which are carried by the shaft 17 have their upper portions extending eccentrically beyond the upper surfaces of the stropping members carried by the shaft 10 while the lower portions of the honing members extend into the grooves or channels 12 between the flanges or ribs 11 on the shaft 10. Similarly of course, the lower portions of the stropping members project eccentrically beyond the peripheral faces of the honing members carried by the shaft 17. Thus, when rotation is imparted through the medium of the gearing above described, it will be seen that the honing and stropping members in one set will be respectively rotated about relatively spaced fixed axial centers in eccentric relation to each other in a clockwise direction, while the honing and stropping members in the other set will be similarly rotated in an anti-clockwise direction. In other words, since the cutting edges of the blade rest upon the upper surfaces of the active members, these members in each set will be rotated in directions away from the respective blade edges.

As the edges of the blade are thus honed, the blade carrying frame is also moved axially by the rotation of the cam members 65 in the manner above described so that notwithstanding the spaced apart relation of the honing members, all portions of the blade edges will receive equal abrasive action. For this purpose, it is not necessary that the extent of reciprocating movement of the blade in each direction shall greatly exceed the width of a honing member and of a stropping member.

Referring now to Figs. 6 and 8 of the drawings, it will be seen that during the reciprocating motion of the blade in contact with the honing members, the blade is disposed substantially in a horizontal plane and its edges bear with equal pressure upon the spaced sets of honing members. As the frame carrying the blade holder approaches the end of its movement in one direction, the inclined flange 70 carried by one of the links 61 comes into position in the plane of the cam arm 68 carried by one of the shafts 10. This flange is thereupon engaged by the curved edge of the cam and is of sufficient width so that in the continued rotation of the shaft 10, said cam exerts an upward bearing pressure, directly lifting the link 61 to which the cam is attached and thereby also lifting the blade holder and the other links attached thereto. Since the ends of the links pivotally connected with the ends of the blade holder must move in definite arcs, it will be apparent that the blade holder must be turned or swung between the ends of the opposed links which are pivotally connected therewith.

The cam continues in contact with the flange 70 until shortly after the dead center position of the blade holder is passed so that the upper end of the link to which said flange is fixed will be at a slightly higher elevation than the upper end of the opposed link in the same pair. Thus, when the cam finally moves out of contact with the flange 70, as indicated in Fig. 8 of the drawings, the springs 64 and the action of gravity will cause the links to swing downwardly and complete the turning movement of the blade holder and the razor blade so that the inner ends of the link

members connected with the holder will assume a superimposed relation to each other which is the reverse of that which they formerly occupied. Therefore, it will be apparent that the opposite beveled faces of the cutting edges of the blade will now engage the honing members as the direction of reciprocating movement of the blade is reversed. These operations may be continued for a predetermined period of time. After the blade edges have been sufficiently honed, and it is desired to then strop the same, the operator by means of the handle 43 and link connections 40, then shifts the bars 30 and 31 to the left from the position shown in Fig. 3, thus depressing the ends of the shafts 17 into the lower ends of the obliquely inclined slots 39 while raising the ends of the shafts 10 into the upper ends of the reversely inclined channels or recesses 37. This changed position of the parts is shown in Figs. 9 and 10 of the drawings, and it will now be seen that the upper portions of the stropping members 23 have thus been projected above the peripheral surfaces of the honing members 26 on the shaft 17, the latter entering the spaces or channels 12 while the lower portions of said stropping members enter the spaces between the honing members and the latter project eccentrically beyond the lower portions of the stropping members.

In this relative shifting movement which changes the centers of rotation of the two shafts 30 and the honing and stropping members carried thereby, it will be understood that the gears 54 and 55 fixed upon said shafts also shift therewith, but nevertheless remain in meshing contact with the wide driving gear 47. It will now be apparent that in the continued reciprocating motions of the blade carrying frame, the edges of the razor blade will have contact only with the stropping members 23. At the end of the reciprocating motion in each direction, the position of the blade will of course, be reversed as above explained so that both sides of its cutting edges will be properly stropped.

If desired, the device may also be used with the honing and stropping members simultaneously in contact with the cutting edges of the blade. In order to thus dispose the cutting and stropping members for rotation about a common center and with their peripheral surfaces in the same circumferential plane, the bars 30 and 31 are shifted until the spring 46 seats at its free end in the central notch 45, thereby positioning the ends of the shafts 10 and 17 midway between the opposite ends of the channels 37 and slots 39 respectively, and with their axial centers in coinciding relation. Therefore, the blade edges will rest throughout their length upon both the honing and stropping members and since the extent of reciprocating motion of the blade is in excess of the width of the individual honing and stropping members, it will be evident that in such reciprocating movements, all portions of the blade edges will be successively and equally honed and stropped throughout the length thereof.

From the foregoing description considered in connection with the accompanying drawings, it will be seen that I have devised a device of relatively simple construction whereby razor blades, and particularly those of the safety razor type, when they have become dulled, can be easily and quickly re-sharpened and provided with cutting edges of the same keenness as the original blade. Since the operation of such a device does not require exceptional skill, it is well designed for

use by the individual, who is thus enabled to re-sharpen such razor blades without resort to the services of an expert. Also by combining both the honing and stropping actions in one device 5 of small dimensions, the necessity of using the usual additional stropping leather is obviated. As the several mechanical parts of the device are also of simple form, they are not likely to readily get out of order, or the device rendered 10 inoperative by abusive handling or use.

As heretofore noted, the above described mechanical arrangements permitting of the relative eccentric shifting of the honing and stropping members and the means for imparting rotative 15 movement to these members is largely suggestive, and I accordingly, reserve the privilege of resorting to various other mechanical expedients as well as variations in the form and construction 20 of the several cooperative parts of the mechanism whereby the purposes of my present invention may be fully accomplished, and as may be fairly incorporated within the spirit and scope 25 of the invention as claimed.

I claim:

1. In a razor blade sharpening device having a blade holder therein, a series of cylindrical honing discs and a series of stropping discs alternately arranged with respect to the honing discs, means for bodily shifting the respective 30 series of discs as separate units to dispose either series of discs at will in position for operative engagement with the edge of the razor blade while rendering the other series of discs inoperative, and means for rotating said discs when 35 in operative position.

2. In a razor blade sharpening device having a blade holder therein, a series of honing members and a series of stropping members alternately arranged with respect to the honing members, a separate axis for each series of members, a common adjustable supporting means for said axes, and said supporting means having parts 40 cooperating with the respective axes in the adjustment of said supporting means to eccentrically position either series of members at will in position for operative engagement with the edge of the razor blade while rendering the other series of members inoperative, and means for rotating said series of members when in operative position.

3. In a razor blade sharpening device having a blade holder therein, a series of cylindrical honing discs, a series of cylindrical stropping discs alternately arranged with respect to the honing discs, a separate axis for each of said 50 series of discs, and means for rotatably mounting said series of discs including manually adjustable means operatively engaged with the axes of said series of discs to shift either series of said discs at will to an eccentric position relative to the other series of discs for exclusive operative engagement with the edge of the razor blade.

4. In a razor blade sharpening device having a blade holder therein, a series of cylindrical honing members, a series of cylindrical stropping members alternately arranged with respect to the honing members, a separate axis for each of said series of members, and means for rotatably mounting said series of members including manually adjustable supporting means common to the axes of both series of members and having parts to coact with said axes and support said members for rotation about a common center to simultaneously engage the edge of the

razor blade, or to bodily shift said series of members in relatively opposite directions from such common center to eccentrically position the honing and stropping members with respect to each other and dispose a selected series of members in position for operative engagement with the edge of the blade while rendering the other series of members inoperative.

5. In a razor blade sharpening device having a blade holder therein, a series of cylindrical honing members, a series of cylindrical stropping members alternately arranged with respect to the honing members, a separate axis for each of said series of members, supports common to the axes of both sets of members having surfaces extending in oppositely inclined planes and constituting bearing seats for the ends of the respective axes, and means for rectilinearly shifting said supports relative to said axes, said inclined bearing surfaces coacting with the respective axes to radially move the same relative to each other and thereby bodily shift the respective series of members and position a selected series of said members for operative engagement with the edge of the razor blade and disposing the other series of said members in an inoperative position.

6. In a razor blade sharpening device having a blade holder therein, cylindrical sharpening members arranged in axially juxtaposed relation and each of said members being bodily movable in its own plane, means for rotatably supporting said sharpening members including an axis having a fixed connection with each of said members and extending in opposite directions therefrom, and means for rotatably supporting said members consisting of elongated bearing seats for the ends of each axis, the bearing seats at the corresponding ends of said axes extending in opposite obliquely inclined planes and in fixed relation to each other, and means for adjustably positioning said bearing seats and thereby causing the same to coact with the ends of the respective axes and radially move the same relative to each other whereby said blade sharpening members are shifted to relatively eccentric positions to dispose one of said members in operative contact with the edge of the razor blade and simultaneously move the other of said members to an inoperative position.

7. In a razor blade sharpening device having a blade holder therein, cylindrical sharpening members of the same diameter arranged in axially juxtaposed relation and each of said members being bodily movable in its own plane, means for rotatably supporting said sharpening members including an axis having a fixed connection with each of said members and extending in opposite directions therefrom, and means for rotatably supporting said members consisting of elongated bearing seats for the ends of each axis, the bearing seats at the corresponding ends of said axes extending in opposite obliquely inclined planes and in fixed relation to each other, and means for adjustably positioning said bearing seats and thereby causing the same to coact with the ends of the respective axes and radially move the same relative to each other whereby said blade sharpening members are shifted to relatively eccentric positions to dispose one of said members in operative contact with the edge of the razor blade and simultaneously move the other of said members to an inoperative position, or positioning said members in concentric relation for rotation about a common center in

simultaneous operative contact with the edge of the razor blade.

8. In a razor blade sharpening device, cylindrical alternately disposed disc members of different abrasive properties adapted to engage the cutting edge of a razor blade, means for adjustably positioning said members in eccentric relation to each other to dispose a selected member in position for operative engagement with the edge of the blade, means for reciprocating a razor blade disposed in a horizontal position with its edge extending axially of the sharpening member, said means consisting of a frame, a holder for the razor blade, overlapping linkage means mounted in the frame and connected with said holder for yieldingly urging the blade edge into contact upon the peripheral surface of the sharpening member, and means for reciprocating said frame, said linkage means being held in yieldably operable position by springs for keeping the blade in contact with the surface of the sharpening member.

9. In a razor blade sharpening device, rotatably mounted alternately disposed disc members of different abrasive properties having their axes disposed in spaced relation to each other, means for rotating said members in relatively opposite directions, and means for reciprocating a razor blade between said members axially thereof and with its opposite edges bearing upon the peripheral surfaces of the respective members, said means consisting of a frame, a holder to removably receive the razor blade, means mounted in the frame and connected with the blade holder to support the blade in a horizontal position and yieldingly hold its edges in contact with the respective sharpening members, and means for reciprocating said frame, said linkage means being held in yieldably operable position for normally keeping the blade in contact with the surface of the sharpening member.

10. In a razor blade sharpening device, rotatably mounted sharpening members having their axes disposed in spaced relation to each other, means for rotating said members in relatively opposite directions, means for reciprocating a razor blade between said members axially thereof and with its opposite edges bearing upon the peripheral surfaces of the respective members, said means consisting of a frame, a holder to removably receive the razor blade, means mounted in the frame and connected with the blade holder to support the blade in a horizontal position and yieldingly hold its edges in contact with the respective sharpening members, means for reciprocating said frame, and means automatically operating at the end of the reciprocating movement of the frame in each direction to turn the blade holder through an arc of 180° relative to its supporting means and thereby dispose the opposite sides of the blade edges in contact with the respective sharpening members.

11. In a razor blade sharpening device, rotatably mounted sharpening members having their axes disposed in spaced relation to each other, means for rotating said members in relatively opposite directions, means for reciprocating a razor blade between said members axially thereof and with its opposite edges bearing upon the peripheral surfaces of the respective members, said means consisting of a frame, a holder to removably receive the razor blade, spaced pairs of links pivotally mounted at one of their ends in the frame, the other ends of said links being pivoted in spaced relation to each other to the blade

holder and supporting said holder with the razor blade disposed in a horizontal position and in bearing contact at its opposite edges upon the respective sharpening members, means for reciprocating said frame, and cam means automatically coacting with one of the links in each pair at the end of the movement of the frame in each direction to turn said blade holder and the blade through an arc of substantially 180° and position the opposite sides of the blade edges in contact with the sharpening members.

12. In a razor blade sharpening device, two sets of rotary members laterally spaced from each other, and each set including alternately arranged honing and stropping members, manually adjustable means cooperating with the axes of said members to simultaneously shift the respective honing and stropping members in both sets to eccentric positions relative to a common center and selectively position the honing members or the stropping members for engagement with the respective cutting edges of a double edged razor blade, and means for supporting the razor blade between said members and reciprocating the same axially thereof with its edges in contact with the operatively positioned members in the respective sets.

13. In a razor blade sharpening device, two sets of rotary members laterally spaced from each other, and each set including alternately arranged honing and stropping members, manually adjustable means cooperating with the axes of said members to simultaneously shift the respective honing and stropping members in both sets to eccentric positions relative to a common center and selectively position the honing members or the stropping members for engagement with the respective cutting edges of a double edged razor blade, means for supporting the razor blade between said members and reciprocating the same axially thereof with its edges in contact with the operatively positioned members in the respective sets, and means for automatically reversing the position of the razor blade at each end of its reciprocating motion to dispose the opposite sides of the blade edges in contact with said members.

14. In a razor blade sharpening device, two sets of rotary members laterally spaced from each other, and each set including alternately arranged honing and stropping members, manually adjustable means cooperating with the axes of said members to simultaneously shift the respective honing and stropping members in both sets to eccentric positions relative to a common center and selectively position the honing members or the stropping members for engagement with the respective cutting edges of a double edged razor blade, means for supporting the razor blade between said members and reciprocating the same axially thereof with its edges in contact with the operatively positioned members in the respective sets, means for automatically reversing the position of the razor blade at each end of its reciprocating motion to dispose the opposite sides of the blade edges in contact with said members, and means operatively connected with said blade reciprocating means for rotating the two sets of honing and stropping members in relatively opposite directions.

15. In a razor blade sharpening device comprising a blade holder, cylindrical sharpening members adapted for operative engagement with the blade, said sharpening members comprising a plurality of alternate discs of different abrasive surfaces, one set of said sharpening members being

mounted on a tubular shaft, the other set of said sharpening members being mounted on a shaft which passes within the tubular shaft, means for positioning either set of sharpening members in operative engagement with the blade, and means for rotating the sharpening members.

16. In a razor blade sharpening device, comprising a casing, a blade holder therein, opposed cylindrical sharpening members adapted for operative engagement with the blade, said sharpening members comprising a plurality of alternate stropping and honing discs, said stropping discs being mounted on a tubular shaft, and eccentric means within said shaft for mounting the honing discs to provide for selective operative engagement of the blade with the honing or stropping discs, and means for rotating the sharpening members.

17. In a razor blade sharpening device, opposed cylindrical sharpening members, a blade holder adapted to hold the edges of one side of a double edge blade in operative engagement with the sharpening members, said blade holder and sharpening members being movable longitudinally relatively to each other while the blade remains in contact with the sharpening members, linkage members attached to said blade holder for lifting up the blade from operative engagement with the sharpening members, swinging the blade through an arc of about 180° in the air, around the longitudinal axis of the blade, and lowering the blade into operative engagement with the sharpening members again so that the two edges of the other side of the blade which had previously not been in engagement, are now in operative engagement with the sharpening members, and means for rotating the sharpening members.

18. In a razor blade sharpening device, a rotatable cylindrical sharpening member, a blade holder adapted to hold the edge on one side of a blade in operative contact with said member, said blade holder and sharpening member being movable longitudinally relatively of each other while the blade remains in contact with the sharpening member, linkage members attached to said blade holder for lifting the blade holder from operative contact with the member, and swinging the blade through an arc of 180° in the air around the longitudinal axis of the blade and lowering the blade into operative engagement with the sharpening member again so that the other side of the blade edge is in operative contact with the member, and means for operating the linkage members.

19. In a razor blade sharpening device, a plurality of shafts capable of rotary movement about a common axis of rotation, cylindrical alternately disposed honing and stropping members mounted on the shafts adapted to engage the cutting edge of a razor blade, means in connection with said shafts for adjustably positioning said members relative to each other to dispose the selected members in position for operative engagement with the edge of the blade thereby displacing the centers of rotation of the shafts from coincidence, a holder to support the blade with its edge in contact with the operative sharpening members, and means in connection with the holder for reciprocating said blade and holder axially of the sharpening members to move the blade edge longitudinally thereof across the face of the honing and sharpening members.

20. In a razor blade sharpening device having a blade holder therein, alternately disposed sharpening members of different surfaces, a separate

axis for each type of sharpening member, supporting means for said axes, cams at the free axial end of each member, linkage members operated by said cams, a carriage frame for the linkage members, a guider member for moving said carriage frame whereby to move the blade holder relatively of the sharpening members, means cooperating with the respective axes in adjustment of the supporting means to eccentrically position either type of sharpening means at will in position for operative engagement with the edge of the razor blade while rendering the members of the other type inoperative, and means for rotating said members when in operative position.

21. In combination a plurality of shafts rotatable about a common axis of rotation, a plurality of members one affixed on each of said shafts and having operative surfaces extending the same distance from the axes of the shafts on which they are affixed, a member to be operated upon by said operative surfaces, and means for displacing the axes of rotation of the shafts from coincidence whereby the operative surface of the member of one shaft may be eccentrically disposed with respect to the operative surface of the member of the other shaft and brought into operating engagement with the member to be operated upon, the other operative surface being out of operating engagement therewith, and means in connection with the shafts for imparting rotary movement to said shafts, while the operative surface of the eccentrically disposed member is in engagement with the member to be operated upon.

22. In a device, a shaft having sectors mounted thereon and spaced apart, rings mounted on said sectors with their peripheral surfaces concentric with the axis of said shaft, a plurality of sectors spaced apart and in opposed staggered relation to the sectors on the first shaft and having rings mounted thereon, the peripheral surfaces of the second rings being of the same shape as those of the first rings, means intermediate each of the second set of sectors for longitudinally connecting said sectors, tubular shafts connected with the end sectors and extending therefrom and surrounding the first-named shaft, the axes of the tubular shafts being coincident with each other and concentric with respect to the surfaces of the second set of rings, whereby, when the axes of the shafts are in coincidence the surfaces of the two sets of rings are in alignment with each other, and when the axes of the shafts are not in coincidence, the surfaces of the rings mounted on one of the shafts are eccentrically disposed in respect to the surfaces of the rings mounted on the other of said shafts, a member to be operated upon by either set of rings, means moving one of the axes of the shafts from its coincident position with the other shaft towards the member to be operated upon, whereby the rings on the shaft whose axis is nearest the member act on said member, and means for rotating the rings acting on said member.

23. In a device, a frame, operative members in said frame, a holder, a member in said holder normally in operating engagement with said operative members, and means for moving the member in said holder away from operating engagement with said operative members in order to turn the member 180° and for restoring it to operating engagement with said operative members, said means comprising pivotal connections on the holder disposed equi-distant from the axis of the holder, link members each pivotally

supported at one end to the frame and pivotally connected at the other end to the pivotal connections on the holder, means for imparting a circular movement around its pivotal support to the pivotal connection of one link member on the holder to the limit of its movement, the pivotal connection of the other link member moving with it through the interposed holder, and means for imparting a circular movement to the pivotal connection of the other link member on the holder around its pivotal support in a direction opposite to its previous movement, the first link member now moving with the second link member through the interposed holder until the member in the holder is returned to operating engagement with the operative members, whereby said holder is swung through 180° and the member in the holder is restored to operating engagement with the operative members but turned 180° from its former position.

24. In a device, a frame, a member in said frame, a holder, a member in the holder normally in operating engagement with said member in the frame, and means for moving the member in the holder away from operating engagement with the member in the frame in order to turn the member in the holder 180° and restoring it to operating engagement with the member in the frame, said means comprising pivotal connections on the holder disposed equidistantly from the axis of the holder, link members each pivotally supported at one end on the frame and pivotally connected at the other end to the pivotal connections on the holder, the link members being of the same length and the line connecting the pivotal supports passing through the point of engagement of the member in the holder with the member supported in the frame when in engagement, and said pivotal connections being arranged at right angles to said connecting line when the said members are in such engagement, the movement of the pivotal connections of said holder bearing a leading and lagging relationship to each other when the member in the holder is moved out of said engagement, means for imparting to one link member around its pivotal support a rotary movement to the limit of its movement for moving the pivotal connection which lags behind the other pivotal connection, and means for imparting to the other link member around its pivotal support, when the first pivotal connection reaches the limit of its movement, a rotary movement for moving the other pivotal connection in a direction opposite to its previous movement, whereupon said means acting on the first pivotal connection is released, and said means acting on the other pivotal connection returns the member in the holder to operating engagement with the member supported by the frame, whereby the said holder is swung through 180° and the member in the holder is restored to operating engagement with the operative members.

ment with the member supported by the frame but turned 180° from its former position.

25. In a razor blade sharpening device, a frame, a holder for a blade, pivotal connections on the holder disposed equi-distantly off-center and on a line substantially at right angles to the plane of the blade, members pivoted to said pivotal connections and to the frame, means for imparting a rotary movement to one of the members around its pivotal support on the frame whereby the other member is moved, and means for imparting a rotary movement to the other member around its pivotal support in a direction opposite to its previous movement and when the first said member has reached the limit of its movement, thereby swinging the holder through 180° and reversing the blade, and means adapted to operate upon the blade.

26. In an abrading device, the combination of a work holder, an abradant-carrying member for abrading the work placed in said holder comprising shaft elements whose axes of rotation are adjustable eccentrically with respect to each other, and separate series of abrading elements of different abrasive qualities supported by the respective shaft elements and movable therewith, means for adjusting said shaft elements in respect to the eccentric positions thereof for causing contact of a selected series of abrading elements with the work placed in said holder while freeing the other series of abrading elements from contact with the work, and operating means acting on the shaft element carrying the selected series of abrading elements for abrading the work by the selected series of abrading elements while in contact with the work.

27. In an abrading device, the combination of a work holder, a plurality of abradant-carrying members for abrading the work placed in said holder, movable and independent bearings, each abradant-carrying member comprising a shaft element mounted in said movable and independent bearings and an abrading element supported on each shaft element and movable therewith, said abrading elements being of different abrasive qualities, and said shaft elements being adapted to rotate around a common axis of rotation when the said bearings are in alignment, means for relatively adjusting the position of the bearings of the shaft elements of the abradant-carrying members for positioning the axis of rotation of the shaft element of an abradant-carrying member of a selected abrasive quality eccentrically to the position of the axes of rotation of the shaft elements of the other abradant-carrying members, to cause contact of the selected abrading element with the work placed in said holder while preventing contact of the other abrading elements with the work, and operating means acting on the selected abradant-carrying member for abrading the work by the selected abradant-carrying member while in contact therewith.

ALBERT RUCKGABER.
